(57) **CLAIM**

We claim the ornamental design for a screen mounting tube, as shown and described.

DESCRIPTION

FIG. 1 is a perspective view of a screen mounting tube;

FIG. 2 is a top end view thereof;

FIG. 3 is a right side view thereof;

FIG. 4 is a left side view thereof;

FIG. 5 is a top side view thereof;

FIG. 6 is a bottom side view thereof; and,

FIG. 7 is a bottom end view thereof.

The drawings contain a symbolic break. The portion between the break lines forms no part of the claimed design. Moreover, the drawings contain dashed lines. The dashed lines represent portions that form no part of the claimed design.
